UNITED STATES PATENT OFFICE.

HENRY W. DIECK, OF BROOKLYN, NEW YORK, ASSIGNOR TO THE STANDARD TEXTILE PRODUCTS COMPANY, OF NEW YORK, N. Y., A CORPORATION OF OHIO.

DESIGN FOR A TABLE COVER OR SIMILAR ARTICLE.

Application filed February 8, 1928. Serial No. 25,279. Term of patent 3½ years.

To all whom it may concern:

Be it known that I, HENRY W. DIECK, a citizen of the United States, residing in the borough of Brooklyn, county of Kings, and State of New York, have invented a new, original, and ornamental Design for Table Covers or Similar Articles, of which the following is a specification, reference being had to the accompanying drawing, forming part thereof.

The figure of the drawing is a top plan view of a table cover showing the border design in detail in the lower left-hand corner, which design is repeated in the other three corners. The dot and dash lines indicate one-fourth of the cover. The center cluster of the design is shown in its entirety.

I claim:

The ornamental design for a table cover or similar article, as shown and described.

HENRY W. DIECK.
